(57) **CLAIM**

(21) Appl. No.: **29/139,869**

The ornamental design for chip for personal digital assistant, as shown and described.

(22) Filed: **Apr. 5, 2001**

DESCRIPTION

(51) LOC (7) Cl. **14-02**

FIG. 1 is a front perspective view of a chip for personal digital assistant according to the present invention;

(52) U.S. Cl. **D14/434; D14/435**

FIG. 2 is a front elevational view thereof;

(58) Field of Search .... **D14/432, 433, D14/434, 300, 356, 357; D13/184, 199; 361/679-687; 200/5 R, 5 A, 6 R, 6 A**

FIG. 3 is a right elevational view thereof;

FIG. 4 is a rear elevational view thereof;

(56) **References Cited**

FIG. 5 is a front perspective view of a chip for personal digital assistant according to the present invention, connected to a personal digital assistant;

U.S. PATENT DOCUMENTS

FIG. 6 is a right elevational view thereof; and,

FIG. 7 is a rear elevational view thereof.
